Toshiyuki Yokoi(57) **CLAIM**

The ornamental design for a battery for computer, as shown and described.

DESCRIPTION

FIG. 1 is a front view of a battery for computer showing our new design;

FIG. 2 is a rear view thereof;

FIG. 3 is a right side view thereof;

FIG. 4 is a left side view thereof;

FIG. 5 is a top view thereof;

FIG. 6 is a bottom view thereof;

FIG. 7 is a rear and left perspective view thereof; and,

FIG. 8 is a front and right perspective view thereof.

In the drawings, the broken lines are for the purpose of illustrating portions of the battery for computer that form no part of the claimed design.
